AUTOMOBILE LOCK

Original Filed Sept. 26, 1927

UNITED STATES PATENT OFFICE

ORVILLE S. HERSHY, OF CHICAGO, ILLINOIS, ASSIGNOR, BY MESNE ASSIGNMENTS, TO
OAKES PRODUCTS CORPORATION, OF NORTH CHICAGO, ILLINOIS, A CORPORATION OF
MICHIGAN

AUTOMOBILE LOCK

Application filed September 26, 1927, Serial No. 221,871. Renewed January 15, 1932.

This invention relates to a coincidental lock adapted for automobiles generally and is designed particularly for association with one of the operating units thereof. It may be connected with a steering mechanism, a change speed mechanism, a motor ignition circuit, or any other unit or system whose operation is required in the use of a motor vehicle.

10 The embodiment of my invention herein disclosed includes a switch which may be interposed in the motor ignition circuit. Such a switch is designed to be opened, thereby rendering the motor inoperative, whenever 15 the lock is operated to interfere with use of an associated mechanism.

The present invention is concerned with certain improved features in the connection between the lock and switch by which the 20 latter may be opened or closed independently of any lock operation; it provides also for a two-stage operation in which actuation of the switch must precede movement of the lock, or vice-versa. This successive operation is 25 effected through double control means requiring separate manipulation before both stages of operation can be completed. My invention is concerned also with an improved switch mechanism which is associated with 30 the lock, and with the arrangement of certain conductors extending from the switch to a remote point for connection with binding posts which are located accessibly in a desired position.

35 Objects such as these, as well as others which will hereinafter appear, are set forth in the accompanying drawing wherein I have illustrated a suggestive construction in the manner following:

40 Figure 1 is a longitudinal section through a steering column with which is associated the present lock and switch, both of which appear in section;

45 Fig. 2 which is an end elevation of the lock exhibits in transverse section the switch which is associated therewith;

Fig. 3 is a bottom plan view of the switch housing shown in relation to the steering column which appears in transverse section;

50 Fig. 4 is a detail in perspective of one of

the conductor bars which connects with the switch;

Fig. 5 is a view in elevation of the switch housing looking toward the side thereof which is proximate to the steering column; 55

Fig. 6 is a detail in perspective of the slide assembly forming part of the switch;

Fig. 7 is a top plan view of the switch slide and housing in which the same is mounted;

Fig. 8 is a longitudinal section through the 60 switch taken on line 8—8 of Fig. 7; and

Fig. 9 is a view of the switch guide plate per se.

The present lock may be contained within a casing A which, in the form shown, is provided with a collar 10 adapted to surround a steering column B. Extending within the column is the usual post C for connecting the steering wheel with the swiveled running wheels at the front of the vehicle. Secured 70 fast to the post C is a bushing D wherein is a groove or socket 11 which may be brought into register with a corresponding opening formed in the column. Extending laterally 75 from the lock casing is an arm 12 forming a bracket for connection with a dash or instrument board, or other fixed part of the vehicle, whereby to provide a support for the column.

Within the lock casing is a cylindrical aperture wherein is mounted a hollow plunger 15 equipped at its outer end with a laterally extending handle 16 forming an operating lever by which oscillatory movements may be performed. Within the plunger is slidingly received a locking bolt 17 flattened at one side to provide a recess having at one end a stop shoulder with which may engage a plate 18 carried by the plunger. By this means I limit 85 the movement of the bolt outwardly from the plunger. A compression spring 19 within the plunger bears with pressure against one end of the bolt so as to project the same yieldingly to locking position. Reciprocatory movements of the plunger are controlled by a lock cylinder 20 operable with a key 21 which is 90 specially designed therefor. The cylinder is disposed with its axis transverse to that of the plunger, and carries upon its rear or inner end an eccentric 22 slidably disposed with-

95

Fig. 2 which is an end elevation of the lock exhibits in transverse section the switch which is associated therewith;

Fig. 4 is a detail in perspective of one of

100

in a cross slot 23 in the plunger whereby to impart longitudinal movements thereto when the locking cylinder is rotated. It is contemplated that the key shall be removable from 5 the lock cylinder only in either of its extreme positions, which, as shown, are 180 degrees apart.

The lock herein set forth is one which is admirably suited for the purpose of this invention. It may include also a position indicator in the form of a double walled disk 24 10 slidable within a guideway 25 which is disposed across the face of the lock casing, as shown in Fig. 1. Through an aperture 26 in 15 the guideway appropriate characters carried on the disk are exposed to view. This disk is shifted within the guideway in response to movements of the plunger by means of a laterally extending pin 27 which engages slidably 20 within an oblique slot formed in one wall of the disk. By this construction the disk is caused to shift its position within the guideway whenever the plunger is reciprocated or oscillated.

25 As part of the bolt assembly I provide also a second pin 28 which may be extended laterally from the plunger in a direction which is opposite to that of the pin 27. This latter pin 28 accordingly projects toward the 30 rear or under side of the lock casing where I have provided a slot 29 extending through the wall thereof in parallelism with the axis of the plunger. This slot is open at the end adjacent the control lever 16 to allow entrance 35 of the pin 28 when the plunger is assembled within the lock casing. Any suitable means may be employed for yieldingly holding the plunger in a selected rotative position while executing a reciprocatory movement.

40 The lock structure just described, in its principal aspects at least, has heretofore been known. It is here shown and described in detail for a better understanding of its cooperation with a switch mechanism which is adapted 45 for association therewith, and, in a measure, for controlling the operation thereof. The details of this switch construction will now be described.

As shown, I have provided a housing E of 50 insulated material which may conveniently be formed in a die moulding, the housing being designed for the reception of the switch parts and also of certain conductors leading therefrom to binding posts which are located 55 at a remote point. A switch chamber 30 is provided at one end of the housing which is attachable to the lock casing with the aid of screws (not shown) which extend through one or more holes 31. The switch may accordingly 60 be positioned relative to the steering column upon the same side thereof as are the operating parts of the lock mechanism already described, preferably to the right as viewed by the operator. The switch housing 65 is formed with a lateral extension 32 which

passes around the column preferably to the rear side thereof, for supporting certain binding posts 33 to which electrical conductors are connected in the usual manner.

Upon the outer face of the switch housing 70 which lies adjacent the lock casing, I provide a shallow recess 34 forming a seat for a guide plate 35 through which is formed an L-slot having longitudinal and transverse branches 36 and 37, respectively. When the switch housing is secured in place, this guide plate is immovably confined in place.

The switch herein shown is designed to operate with a three-wire system. It includes 80 three stationary contacts, each formed by a stud 38 and each having an exposed socketed end 39 substantially flush with the sunken face of the switch chamber. Each stud carries a pair of spaced flanges 40 between which is received the forked end of a conductor bar 41 which leads to one of the binding posts 33 at the far end of the switch arm 32. With each conductor bar I associate an insulating strip 42 having its ends forked for connection with the associated stud 38 and binding post 33. 85 By this arrangement, which provides for a strip of insulating material between each of the conductor bars, the connections so leading from the fixed contacts to the binding posts may be disposed contiguously in which relation they are maintained within the moulding forming the switch housing.

The three fixed contacts of the switch are arranged by preference in triangular formation, two being adjacent one end wall at the 100 chamber 30 and the third adjacent the opposite end wall thereof. Mounted to reciprocate between these two walls of the housing is a slide F which may be advantageously formed of two parts, viz., an insulating block 105 43 and a conductor plate 44 having three buttons 45 corresponding in positions to the fixed contacts and projecting toward the same. The plate may also be formed with certain upstanding lugs 46, three being a suggested number, each adapted to enter a groove 47 extending transversely of the block 43 whereby to center the one movably with respect to the other. Between the block and plate are located coiled springs 48, one preferably in line with each button 45, each spring being accommodated in part within a recess which is formed in the block. The slide so constructed is adapted to be confined in place between the sunken face of the switch chamber and the guide plate 35 where it may reciprocate to either of two positions. By providing at one end of the guide plate an upstanding flange 49, the opening at the end of the casing slot 29 is effectively closed.

In the outer face of the slide block, I provide an elongated slot 50 which extends through to one end thereof. In this slot is received the projecting end of the pin 28 which is extended laterally from the plunger 125

15. This pin which is required to pass through the L-slot in the plate 35 is guided thereby in all of its movements. When the plunger is in the out position, it may be oscillated due to the fact that the pin 28 is aligned with the transverse branch 37 of this slot. Such a movement will cause the slide to be shifted from one end of the switch chamber to the other. In one of these positions the three buttons 45 will establish contact with the three studs 38 so as to form a common electrical connection therebetween. When so related, the buttons are spring-pressed into the sockets at the exposed ends 39 of these studs so as to be yieldingly retained in this position.

By oscillating the plunger 15, the slide may be moved to the other extreme position where each of the three buttons 45 is removed from contact with the associated studs. In such a case the circuit is broken between all three wires of the electrical circuit. In this latter position the pin 28 lies in the corner formed by the juncture of the slot branches 36 and 37, permitting the plunger then to advance freely by a straight line movement. When the plunger is so moved to an inward position, the pin 28 slides idly within the slot 50 without disturbing the position of the switch. The switch is accordingly incapable of being operated to closed position when the bolt 17 is advanced into locking position relative to the steering post C. It is only when the bolt is completely disengaged from the post by a full retraction of the plunger that the latter can be oscillated to operate the switch to either open or closed position.

The present switch is advantageous in numerous respects. The parts which enter into its construction are simple and easily assembled, and will not wear out over a prolonged period of service. The conductor bars which lead from the switch to a remote point are completely housed in and insulated from each other. In the construction of the switch housing, these several bars which are preliminarily formed to the exact shape desired, are arranged contiguously without danger of short circuiting due to the provision of the insulating strips which separate them properly for this purpose.

I claim:

1. In combination with a movable element, a lock mechanism therefor having a part which is mounted for both oscillatory and reciprocatory movements, a switch in which is a movable element having a slot and means extending from said part into the slot of the movable switch element adapted to impart motion to the latter only when the said part executes one of its movements, substantially as described.

2. In combination with a movable element, a lock mechanism therefor in which is comprised a part adapted for reciprocation or oscillation, a switch associated therewith

having a movable element, and means connected fast with one and slidably with the other adapted to transmit motion to the switch only when said part executes one of its movements, substantially as described.

3. In combination with a movable element, a lock mechanism therefor in which is comprised a part adapted for oscillation and reciprocation, a switch associated therewith having a movable element, a connection between said part and switch element having a sliding engagement with the latter, and guiding means for said connection adapted to direct the movements of said part, the switch element being shifted in response to but one of the movements of said part, substantially as described.

4. A lock mechanism with which is associated a housing wherein is a switch having fixed contacts in connection with an electrical circuit, the housing being formed with an extension, binding posts carried by the extension at a point remote from the switch, and conductor bars connecting the posts with the fixed contacts of the switch, the conductor bars being disposed within the housing extension contiguously with intervening strips of insulation, substantially as described.

5. In a coincidental lock, the combination of an automotive control lock mechanism including a bolt mounted for at least two movements, in one of which the control is locked, an electrical switch mechanism associated therewith and having a movable element, and means movable with the bolt and slidably engaging the movable element of said switch without causing movement thereof during one movement of the bolt, said means being adapted to transmit motion to said movable element when said bolt executes another movement.

6. In combination with a movable element, a lock mechanism therefor including a part having a locking movement and another movement, an associated electrical switch in which is comprised a mounting for fixed contacts and a slotted movable contact, and a pin extending from said part into the slot of the movable contact, said pin and slot connection permitting locking movement of said part independently of movement of said movable contact and adapted to shift the latter relative to the fixed contacts when said part executes its other movement.

7. In combination with a movable element, a lock mechanism therefor including a part having a dual movement and having a connecting means extending laterally therefrom, and a switch having a slotted operating element wherein said connection slides without moving said element when said part is given one of its movements, said connection being operative to move the switch element when said part is given its other movement, a circuit, and fixed contacts controlled by said

switch element during such other movement of said part to open or close said circuit.

8. In combination with a movable element, a lock mechanism therefor including a part having a locking movement and another movement, an associated electrical switch in which is comprised a mounting for fixed contacts and a movable contact, and pin and slot connection between said part and said movable contact, said pin and slot connection permitting locking movement of said part independently of movement of said movable contact and adapted to cause shifting of the movable contact relative to the fixed contacts when said part executes its other movement.

9. In combination with a movable element, a lock mechanism therefor including a locking bolt adapted for reciprocatory and for oscillatory movement, an associated electrical switch in which is comprised a mounting for fixed contacts and a movable contact, means restraining said movable contact against movement except in a direction transversely of the axis of said locking bolt, means locking said bolt against oscillatory movement except when it is in unlocking position, and a connection between said bolt and said movable contact operable to shift said movable contact only when said bolt is oscillated.
